UNITED STATES PATENT OFFICE.

FRANK LOUFEK, OF CEDAR RAPIDS, IOWA.

WHEEL-COMPRESSING MACHINE.

1,378,700.

Specification of Letters Patent.

Patented May 17, 1921.

Application filed August 28, 1919. Serial No. 320,371.

To all whom it may concern:

Be it known that I, FRANK LOUFEK, a citizen of the United States, residing at Cedar Rapids, in the county of Linn and State of Iowa, have invented a new and useful Wheel-Compressing Machine, of which the following is a specification.

This invention relates to spoke setting or wheel repairing machines, especially to those 10 designed for automobile wheel repair work.

The primary objects of this invention are to provide a machine which is adjustable for all types and sizes of automobile or other wheels so as to make repair work quick and 15 easy, which has great strength and simplicity of construction, and which in general is an improvement over all other machines of the type on the market.

The herein described invention is specifically 20 designed as an improvement on the machine disclosed in Patent Number 1,296,198 granted to me March 4, 1919, the aim being to improve the construction of the patented machine to make a stronger, simpler 25 and less expensive mechanism which will turn out equally good work.

To arrive at a complete understanding of the invention, reference should be made to the accompanying drawings which form 30 a part of this specification and illustrate a preferred embodiment of the invention. I do not wish to be limited to the construction disclosed in the drawings, however, but desire to make such changes as may be necessary, provided such changes are within the 35 scope of the appended claims.

In the drawings:

Figure 1 is a perspective view showing the complete machine with a wheel clamped 40 therein;

Fig. 2 is a diametrical vertical cross sectional view of the machine and wheel with the pedestal omitted;

Fig. 3 is a top plan view of the machine 45 and wheel;

Fig. 4 is a detail sectional view of the spoke clamping mechanism.

Fig. 5 is a detail cross section through one of the arms of the support.

In my before-mentioned patent, the main support or framework is formed of four radial arms extending outwardly from a central circular portion, each arm having a rest portion and a ring-supporting portion 50 arranged concentrically with the center of the support and at different elevations. Ap-

plied to the top of the central portion is a separate base plate on which is formed an annular flange threaded to engage with a corresponding flange of a table constituting 60 an adjustable center rest for the wheel. Fixed to the rest portion is an inner threaded ring to which is adjustably connected a threaded annulus. In the present improvements I have dispensed with the adjustable annulus with its threaded ring; I have eliminated the special construction 65 of center rest; I have substituted for the arms disclosed in said patent a construction of arm which is of arch formation imparting great strength to the structure; I have improved the connection between the pedestal and the support, and I have further improved the construction of the means for holding the vehicle wheel to the machine 70 while being operated upon. Though the general principle remains the same, the construction has been much simplified, resulting in a machine which has been found to be capable of withstanding the heavy strains 75 to which machines of this character are subjected.

The numeral 10 in the drawings designates a pedestal of any conventional type whose upper end has an annular flange 15 85 surrounding a cylindrical bearing collar 14. The collar 14 provides a mounting for an armed support 20 which has a cylinder or sleeve 17 mounted to turn about the collar, resting upon the flange 15. The armed support 20 is thus mounted on the pedestal so 90 as to form a turn-table.

The support 20 has a plurality of arms 22, preferably four, extending radially and upwardly in a curved or arched formation 95 from the sleeve 17. Each arm is T-shaped in cross section shown in Fig. 5. A boss 30 is formed centrally on the support 20 and rises therefrom. This boss has a central screw threaded bore 31 and an upstanding annular flange 32 having external screw threads. The several arms with the sleeve 17, boss 30 and flange 32 are all formed in a single casting, and constitute an important improvement over my former patent. 100 A center rest 33 having the depending internally threaded flange 35 engages with the flange 32 so as to be vertically adjustable with respect to the support. The center rest 33 has a central bore 61 through a hub 110 engaging end 59 shaped like a truncated cone with an angle of inclination prefer-

ably between 60° and 70°. The base or lower end of the conical part 59 is preferably larger in diameter than the depending flange 35, as seen in Fig. 2.

5 The arms 22 rise above the turn table to a plane nearly level with the upper end of the hub engaging cone 59. The upper ends 24 of the arms are shaped to provide a ring frame seat 25, and a bracket 26 having a vertical bore 27 for the reception of a bolt 43. This bolt may be hooked at one end as at 44 and having a wing nut 42 for purposes to be described.

Upon the seat 25 is a ring frame composed 15 of two spaced rings 37 held apart by the spacing blocks 38. Each block is secured by bolts, rivets or other means between the rings 37, and there are preferably as many spacing blocks as there are arms to the support. Flanges 40 on the spacing blocks engage with the inner and outer edges of the two rings and help secure the blocks to the latter. Each block is provided with a projecting lug 41. The ring frame is seated so 25 that the blocks can be engaged by means of the lugs 41 with the hooked ends of the bolts 43. Thus by turning the wing nuts 42, the ring frame is tightly clamped in place upon the armed support. It will be 30 clear that instead of using the means for clamping the ring frame which has been described, other well known means might be employed, such as the spring clamping lever described in my former patent.

35 The spaced rings 37 provide a runway or track for a plurality of slide brackets 45. These brackets have a central threaded bore 46, and are held upon the rings by outer flanges 47 and inner flanges 48. The latter 40 have outturned portions 49 which rest upon the outer faces of the two rings and form hook-like projections which guide the slide brackets in any movement on the runway or track. Each slide bracket receives through 45 its threaded bore a crank or setting screw 50 with a swiveled head 51 and a spur 52 to engage the rim of the wheel.

A center clamp is provided to hold down the hub of the wheel while being worked 50 upon. This center clamp is preferably a long bolt 53 which extends centrally through the hub and engages with the threaded bore 31 of the boss 30 by means of an enlarged threaded section 58. The upper section 54 of the bolt is reduced in size, providing an annular shoulder 56, and has threads 55 to hold adjustably an upper hub engaging cone 60, smaller than the lower cone 59, the cone 60 having a central threaded bore 63. The 55 base of cone 60 faces upwardly. A nut 64 with spokes or handles 65 is also threaded on the bolt 53 and can be screwed down to bear against the base of cone 60 to lock the same in place. Obviously the nut 64 could 60 be made integral with the cone 60, thus per-

mitting the latter to be screwed down tight into the hub. The upper end of bolt 53 is provided with a hand wheel 66 to render the turning of the bolt easy.

The operation, uses and advantages of my 70 improvement in wheel compressing machines will be readily understood. When a wheel 67 is to be repaired, it is placed with its hub resting upon the center rest and receiving the clamping bolt. The upper cone and 75 nut hold the wheel tightly in place. The height of the wheel may be adjusted by simply turning the clamped wheel or center rest before the wheel is clamped thereon. The desired degree of clamping action is 80 regulated by turning the hand wheel, which has the effect of separating or bringing together the two hub engaging cones. Since the threads 55 are finer than the threads 58, turning the bolt 53 more rapidly clamps 85 the wheel than screwing down the nut. The outer ring frame is always on a level with the rim of the wheel so that the spoke compressing means shown in Fig. 4 can engage 90 each spoke where it joins the rim. The wheel can be firmly held and turned in either direction because of the turn table. Any spoke or any number of spokes can be compressed readily because the slide brackets 95 are movable in either direction along the runway. The ring frame can be removed from the machine with the wheel under compression, and a spare ring frame substituted thus preventing interruption of work. 100 Nearly all sizes of hubs and rims are accommodated with ease in a machine constructed as described. The mechanism is strong, simple, has few parts, and does a great deal of work with the expenditure of a minimum of time and labor.

105 What is claimed is:—

1. In a wheel compressing machine, a support composed of a plurality of arms, each arm having a curved or arched formation, said arms rising from a central portion consisting of a depending sleeve, a boss above the sleeve, and an upstanding threaded flange rising from the boss, all of said parts being formed from a single casting, an adjustable center rest composed of a hub engaging conical portion and a depending inferiorly threaded flange engaging with the first-mentioned flange, a hub clamping bolt passing through the center rest and engaged with the boss, and a cone mounted on the 110 bolt above the center rest.

2. In a wheel compressing machine, a support, a boss integral with said support, an upstanding annular flange integral with said boss, a center rest adjustably connected with 115 said flange, said center rest having an integral hub engaging portion, means for clamping a wheel upon said center rest, and spoke compressing means mounted on said support.

3. In a wheel compressing machine, a support, an upstanding annular flange having exterior screw threads and formed integrally with said support, a center rest threaded 5 upon said flange and having an upper end formed like a truncated cone for engaging the wheel hub, a hub clamping bolt engaging with the support and having a shoulder bearing against the base of the cone, an up-

per cone mounted on the bolt, and a hand wheel fixed to the upper end of the clamping bolt to provide means for turning the same.

In testimony that I claim the foregoing as my own I have hereto affixed my signature.

FRANK LOUFEK.
